DESIGN FOR A VELOCIPEDe FRAME

Bert J. Anderson, Warsaw, Ind.

Application April 11, 1940, Serial No. 91,606

Term of patent 14 years

To all whom it may concern:

Be it known that I, Bert J. Anderson, a citizen of the United States, residing at Warsaw, in the county of Kosciusko and State of Indiana, have invented a new, original, and ornamental Design for a Velocipede Frame, of which the following is a specification, reference being had to the accompanying drawing, forming part thereof.

Fig. 1 is a perspective view of a velocipede frame showing my new design.

Fig. 2 is a rear elevational view thereof.

I claim:

The ornamental design for a velocipede frame, substantially as shown.

BERT J. ANDERSON.
